UNITED STATES PATENT OFFICE.

WILLIAM H. BAKEWELL, OF ALLEGHENY CITY, PENNSYLVANIA.

CAMP-CHAIR AND COT.

SPECIFICATION forming part of Letters Patent No. 295,971, dated April 1, 1884.

Application filed August 27, 1883. (No model.)

To all whom it may concern:

Be it known that I, WILLIAM H. BAKEWELL, of Allegheny City, in the county of Allegheny and State of Pennsylvania, have invented a new and useful Improvement in Camp-Chair and Cot; and I do hereby declare the following to be a full, clear, and exact description thereof, reference being had to the accompanying drawings, forming part of this specification, in which—

Figure 1 is a perspective view of the device arranged as a camp-chair. Fig. 2 is a view of the device extended and arranged as a cot. Fig. 3 is a detached view of the fastening-hook. Fig. 4 is a detached view of the fastening-eye, and Fig. 5 is a detached view of the pin which engages with the hooks and eyes.

Like letters of reference indicate like parts wherever they occur.

20 My invention relates to the construction of a combined camp-chair and cot; and it has for its object the production of a light, compact, and simple folding camp-chair which can at the will of the user be converted into a cot, 25 whereby the advantages of the two articles of furniture are obtained with great saving of space and cost.

I will now proceed to describe my invention, which is an improvement on a combined camp-chair and cot invented by me, and forming the subject-matter of Letters Patent No. 280,004, dated June 26, 1883, so that others skilled in the art to which it appertains may apply the same.

35 In the drawings, *a* indicates the rear frame, and *b* the front frame, composing the chair or cot. This rear frame, *a*, which, as it forms the back of the chair, exceeds the length of the front frame by one-half, more or less, is 40 composed of two longitudinal bars, *a' a²*, which are slightly curved or bent, and are united or joined by cross-bars *a³*. At the upper end of the frame *a* is a sacking-roller, *c*, to which one end of the sacking *c'* is secured, the opposite end of the sacking being secured to the cross-bar *b³* of the frame *b*. On the ends of the sacking-roller *c* are ratchet-wheels *c²*, and secured to the frame *a* are suitable dogs for locking the roller. Pivoted to the journals of 50 the roller *c* are supplemental legs *d*, which are only used as such when the devices are ex-

tended to form a cot. These legs are connected by a cross-bar, *d'*. They also serve as a clutch-crank, to wind the sacking on the roller *c* by means of the pawls *d²*, which are pivoted there-to, so as to engage with the teeth of the ratchet-wheels *c²*. The roller may, however, be pro- 55 vided with a separate crank for accomplishing the same purpose. Each leg *d* is provided with a pivoted hook, *d'*, which engages with 60 eyes *d⁴* on the frame *a*, so as to brace the legs *d* when they are set to support the head of the cot. On the upper part of each bar *a' a²* of the frame *a* is a slide, *e*, which may be moved 65 up and down, turned on the bar, and secured by a set-screw, pin, or other suitable device at any desired point, and to these slides *e* are pivoted braces or stretcher-bars *f*, having open slots *f'* in their lower ends, which engage with pins *f²*, situated at the lower ends of the bars 70 *a' a²*, so as to form the side pieces or arms of the chair; and when the device is extended to form a cot the bars *f* are stretched across from the frame *a* to the frame *b*, the notches *f'* en-gaging with pins *e'* on the side of the bars *b' b²*, 75 so as to serve as braces. On the lower end of the bar *a'*, on the inner side thereof, is an eye, *g*, and on the lower end of the bar *a²* is a hook, *h*, which eye and hook engage with pins *i i'* on the lower end of the bars *b' b²*, when the 80 device is arranged as a cot.

The frame *b*, when the device is arranged as a chair, is attached to the frame *a* by a simi-lar hook and eye, *g' h'*, engaging with pins *i' i* on the bars *b' b²*, so that the frame *a* and the 85 frame *b* together form a cross or X frame, as shown in Fig. 1. Secured to the under side of the sacking *c'* is a cross-bar, *m*, of a greater length than the distance between the bars *a' a²*. This bar *m*, when the device is in the 90 form of a chair, is placed back of the frame *a*, so that its ends rest and bear against the rear faces of the bars *a' a²*, and thereby the sacking which forms the seat and back of the chair is kept taut.

When the device is to be formed into a cot, the sacking is loosened by releasing the roller *c*, and the bar *m* is turned end first and passed between the bars *a' a²*, so as to allow the sack-ing to be stretched between the upper ends of the frames *a* and *b*.

Hinged to each of the stretcher-bars *f* is a

horizontal arm, n , which extends from the bar, and is hinged or pivoted at its outer end to a supporting rod, o , which rod extends downward and is hinged at its lower end to a 5 ring, o' , which slides on the bar f . This ring is held in place on the bar f by a spring-catch, o^2 . Instead of placing the ring o' on the bar f , it may be arranged to slide on a bar attached 10 to the stretcher-bar or attached to the bar a' 15 of the frame a . When the device is to be used in the form of a cot, or is to be folded for transportation, the ring o' is released from the spring-catch o^2 and is pushed down, thereby bringing the arm n and rod o flat against the 20 stretcher-bar.

In order to change the device when in the form of a chair to the form of a cot, the front frame, b , is disconnected from the rear frame, a , by disengaging the pins i' from the hook g' 25 and eye h' . The sacking c is then unwound from the roller c , and the cross-bar m is passed between the bars $a' a^2$ to the front of the frame a , the pins $i i'$, at the ends of the bars $b' b^2$, are fitted into or engaged with the eye g' and hook h at the end of the bars $a' a^2$, the set-screws x 30 are loosened, the slots f' are disengaged from the pins f^2 , the rings e are brought down on the bars $a' a^2$, and the open slots f' are caused to engage with the pins e' . The arms $n n$ are 35 then brought down on the stretcher-bars f , as already described, and the supplemental legs d are placed in position and secured by the hooks d^2 . This produces a cot, as shown in Fig. 2.

The advantages of my invention are its simplicity, durability, cheapness, lightness, and also the ease and rapidity with which the device may be transformed from a chair to a cot or folded for transportation.

Although I have described the arm n as adapted to my improved chair, it may be fit-

ted in a like manner to the frame of other camp and folding chairs.

Having thus described my invention, what I claim, and desire to secure by Letters Patent, 45 is—

1. The combination, in a combined convertible chair and cot, of the rear frame composed of the side bars $a' a^2$ and cross-bars a^3 , the side bars being provided with eyes $g' g^2$ and hooks $h h'$ at the ends and crossing points of the frame, the front frame composed of the side bars $b' b^2$ and cross-bars b^3 , the side bars being provided with the pins $i i'$ and $i' i$ to engage with the hooks and eyes of the rear frame, 55 and an extensible sacking which connects the front and rear frames, substantially as and for the purposes specified.

2. In a combined convertible chair and cot, the combination of two cross-frames adjustable on each other, an extensible sacking which connects the two cross-frames, and a cross-bar whose length exceeds the distance between the side bars of the rear cross-frame, said cross-bar secured to the sacking at or near the front 60 third thereof, whereby the cross-bar may be made to engage with the rear cross-frame, or may be disengaged therefrom, substantially as and for the purposes specified.

3. In combination with a folding chair, an 70 arm pivoted or hinged at one end to the frame of the chair, a support pivoted or hinged to the arm, a sliding ring to which the arm-support is pivoted or hinged, and a locking device for holding the sliding ring, substantially 75 as and for the purposes specified.

In testimony whereof I have hereunto set my hand this 20th day of August, A. D. 1883.

WILLIAM H. BAKEWELL.
